FOOT-HOLDING SLING FOR CHILDREN'S
HIGH CHAIRS OR THE LIKE

Alvin John Brandon, Stratford, Ontario, Canada

Application January 27, 1945, Serial No. 574,859

12 Claims. (Cl. 155—189)

1

My present invention relates to improvements in foot holding slings for a child's high chair or the like and appertains particularly to a novel design of stirrup-like member, a pair of which are adapted to be suspended out in front of the chair seat and serving to prevent a young child from sliding forwards off the seat or climbing up to stand on the seat, support the feet and legs of the child comfortably and may be so mounted as to hold the usual tray against being raised.

An object of the invention is to provide foot receiving slings that may be easily mounted on any child's high chair or the like, affording ample leg freedom and yet from which the child cannot free its feet, and that does not interfere in any way with the usual use of the chair.

A further object of the invention is to provide child's leg slings that are safe, sure and simple and being inexpensive to manufacture and easy to install are thereby rendered commercially desirable.

To the accomplishment of these and related objects as shall become apparent as the description proceeds, the invention resides in the construction, combination and arrangement of parts as hereinafter more fully described, illustrated in the accompanying drawings, and pointed out in the claims hereunto appended.

The invention will be best understood and can be more clearly described when reference is had to the drawings forming a part of this disclosure wherein like characters indicate like parts throughout the several views.

In the drawings—

Figures 1 and 2 are front and side elevations respectively of a common type of child's high chair to which my slings have been applied.

Figure 3 is an enlarged front elevation of the sling seen on the left in Figure 1; and

Figure 4 is a similarly enlarged side elevation of the sling seen on the right in Figure 1.

Seen in Figures 1 and 2 of the attached drawings is a common type of baby's or child's high chair consisting of legs 5, seat 6, side arms 7 and back rest 8. Hinged to opposite sides of the back rest 8 and normally resting across the side arms 7 near the forward ends thereof is a conventional tray 9 that usually extends out in front to a point considerably beyond the forward edge of the seat 6.

For particular reasons elsewhere mentioned but especially because of the convenient location of the front part of this hinged tray 9 a suitable distance above and ahead of the forward edge of the seat 6 I mount my slings or stirrups 10 there-

2

on. It must be understood however that no particular nor even any part of the tray need carry the slings as they may be suspended from any suitable and/or available support or a special and adjustable suspending member may be additionally provided, the exact nature of which is immaterial.

A possible form the slings may take is shown herein where the same is formed from a single length of strap 11, of leather, fabric or similar material doubled to the shape of a U or loop 12 with the ends or arms 13 turned in a plane at right angles to the strap in the base of the U and terminally embracing an attaching bracket 14. 10. A buckle 15, which may be of the slide type, is provided for one or both ends 13 of the strap 11 to allow of adjusting the length of the sling. A guard member 16 encloses the U or loop 12 on its forward or outer side, extending part way up from the bottom. The outer side of the lower part of the U 12 may be additionally or alternately closed by engaging the male and female parts of the snap fastener 17 carried by the opposite arms near their outer or forward edges, thus forming a pouch-like receptacle for the foot.

Preferably the bottom of the U or loop 12 slopes upwards as at 18 to the back or inner side to afford better grip or frictional engagement with 20. the foot supported therein.

The mounting bracket 14 used in the illustrated embodiment for attaching the stirrups to the front edge of the tray 9, one on either side of centre, is formed in one piece with a pair of rod-like lengths 14a with an enlargement 14b between them and 14c on opposite ends, each enlargement is perforated to accommodate the fastening screws 19. The ends 13 of the strap 11 pass over the spaced rod-like lengths 14a from 30 which the stirrup is thus swingingly suspended.

It has been found best in practice to sling the stirrups with their lower ends or loops substantially level with the chair seat and from the forward edge of the tray since the child cannot lift 40 the tray against the weight of its own feet, neither can it slide its feet forward through the loops because of the enclosing guards 16 nor withdraw the feet from engagement in the slings. Pushing the feet out or pulling them back merely causes 50 the slings to swing upwardly outwards or inwards and in either case to tighten the hold on the feet because of their increasing downward pressure.

Some high chairs have a tray strap 20 that connects tray and seat, holding the tray against 55 being raised and the child from sliding forwards

but with my slings this is usually discarded as superfluous.

From the foregoing description taken in connection with the accompanying drawings, it will be manifest that foot holding slings for a child's high chair or the like are provided that will fulfill all the necessary requirements of such a device, but as many changes could be made in the above description any many apparently widely different embodiments of the invention may be constructed within the scope of the appended claims, without departing from the spirit or scope thereof, it is intended that all matters contained in the said accompanying specification and drawings shall be interpreted as illustrative and not in a limitative or restrictive sense.

Having thus described my invention, what I claim as new and desire to secure by Letters Patent is:

1. A child's high chair comprising the usual legs, seat, back and sides, a member disposed forwardly of the chair and above the seat and a pair of freely swinging foot receiving stirrups suspended therefrom.

2. A child's high chair comprising the usual legs, seat, back and sides, a member supported thereby extending forwardly of the chair and disposed above the level of the seat and a foot receiving sling suspended therefrom.

3. A child's high chair comprising the usual legs, seat, back and sides, a member supported thereby extending forwardly of the chair and disposed above the level of the seat and a pair of spaced foot receiving slings hanging therefrom, mounted one on either side of the centre thereof.

4. A child's high chair comprising the usual legs, seat, back and sides, a member supported thereby extending forwardly of the chair and disposed above the level of the seat and outwardly swinging stirrups slung therefrom and reaching to a point not substantially lower than the level of the seat.

5. A child's high chair comprising the usual legs, seat, back and sides, a member supported thereby extending forwardly of the chair and disposed above the level of the seat and a foot receiving sling partially enclosed across the front suspended therefrom.

6. A child's high chair comprising the usual legs, seat, back and sides, a member supported thereby extending forwardly of the chair and disposed above the level of the seat and a foot-receiving sling suspended therefrom, said sling having a closure on its forward side extending at least part way up from the bottom.

7. For a child's high chair comprising legs, seat, back and sides, a tray hinged to the said back and normally resting on said sides and

child's foot holding means in the form of pouch-like, heel-receiving slings attached to said tray to hold the feet in elevated position and prevent the child sliding forward on said seat.

5 8. For a child's high chair comprising legs, seat, back and sides, a tray hinged to the said back and normally resting on said sides, foot-receiving slings suspended from said tray to prevent the same being lifted by the child and additional means mounted on said chair to prevent the child sliding forwards from the seat.

10 9. For a child's high chair comprising legs, seat, back and sides, a tray hinged to the said back and normally resting on said sides, slings suspended from the forward edge of said tray to receive the child's legs and hold the tray against being lifted and means to hold the child against sliding forward on said seat.

15 10. For a child's high chair, foot receiving slings carried thereby and suspended in advance of the chair seat and on approximately the level thereof, said slings being each formed as a strap doubled in length to provide a U and means for adjusting the length thereof.

20 11. Foot slings for a child's chair or the like to support the back of the child's heels in slightly raised position consisting of straps doubled to form U's, a closure across the forward side of the bottom thereof and means for swingingly supporting the ends of said straps from a point above and in advance of the seat of the chair.

25 12. A pouch-like foot sling for supporting the back of the heel in slightly raised position formed of a strap doubled as a U, the ends thereof turned to a plane at right angles to the lower part of the U, a mounting bracket having a spaced pair of rod-like lengths from which said strap ends are supported and bracket attaching means between them.
